UNITED STATES PATENT OFFICE.

MEIER GEO. HILPERT, OF HARRISBURG, PENNSYLVANIA.

POLYCYCLE.

Application filed March 27, 1920. Serial No. 369,426.

To all whom it may concern:

Be it known that I, MEIER G. HILPERT, citizen of the United States, residing at Harrisburg, in the county of Dauphin and State 5 of Pennsylvania, have invented certain new and useful Improvements in Polycycles, of which the following is a specification.

This invention relates to the general subject of toys, and has particular reference to 10 an improvement in juvenile vehicles of the polycycle type.

To this end the invention has primarily in view a novel device which may not only be adjusted to meet the needs of the growing 15 child but at the same time, by reason of its novel construction may be converted into different types of toys, thereby providing a diversity of amusement which other toys of this type fail to afford. That is to say, the 20 invention aims to provide a device fulfilling the requirements of a polycycle which may be adjusted from a size suitable for a child of one year for instance, to sizes for children of older years, and also converted into 25 adjustable carts or chariots to be pulled instead of propelled, and further, with the handle adjusted rigidly, may be used in the latter form as a scooter which the occupant propels with one foot while occupying a 30 standing position on the platform.

The invention also embodies auxiliary 35 benefits when set up as a polycycle such as safety stops to prevent child slipping off backward, increased wheel base as the seat is increased in height, increased handle height above seat or platform to take care of trunk and arm growth coincidentally with an increased platform height to take care of increased leg length, a suitable foot hold or 40 rest for a second "tail board" occupant which board also affords "tag" number space; and when set up as a cart, benefits, such as safety guards against occupant coming in contact with moving wheels, numerous level adjustments adaptable to hill grades and to afford 45 comfort to occupant; and generally the important benefit of providing a toy for the child holding forth valuable self taught lessons in construction and combination by virtue of the many levels, tongue positions, etc. 50 possible for each adjustment whether one side up or the other.

Accordingly, it will be apparent that the present invention contemplates a convertible

toy which is susceptible of assembly in different combinations to readily provide toys of the type set forth. In this connection it is proposed to provide a novel platform unit which may be supported at the front end by a special wheeled steering unit, and at 55 the rear end by a novel type of wheeled truck unit, both of said wheeled units being capable of facile assembly to expedite conversion and adjustment as desired.

A further and more specific object of the 60 invention is to provide a device which may be made of easily constructed and available parts, thereby meeting manufacturing requirements in a thoroughly practical and satisfactory manner and materially enhancing 65 the value of the invention from a commercial standpoint.

With the above and other objects in view 70 which will more readily appear as the nature of the invention is better understood, the same consists in the novel construction, combination and arrangement of parts herein-after more fully described, illustrated and claimed.

A preferred and practical embodiment of 75 the invention is shown in the accompanying drawings, in which:

Figure 1 is a top plan view of the improved toy.

Figure 2 is a side elevation thereof, the 80 dotted lines indicating some of the adjusted positions.

Figure 3 is a front elevation of the 85 wheeled steering unit.

Figure 4 is a rear elevation of the toy. 90

Figure 5 is a side elevation of the device converted into a cart, full lines in said figure indicating the position of the handle when the device is used as a coaster or scooter and the dotted level lines indicating some of the 95 possible adjustments.

Figure 6 is a detail horizontal sectional view of the steering unit.

Figure 7 is a modified type of wheeled steering unit. 100

Figure 8 is a detail view of a further modified form of steering unit.

Figure 9 is a detail side elevation of a modified type of a rear truck unit.

Figure 10 is a rear elevation of the construction shown in Figure 9. 105

Figure 11 is a detail view of a modified form of foot rest.

Figure 12 is a detail view of a modified type of connection between the steering column and the platform.

Figure 13 is a detail horizontal section 5 of the construction shown in Figure 12.

Similar reference characters designate corresponding parts throughout the several figures of the drawings.

In carrying the present invention into effect the primary object of providing a convertible construction is observed in all individual elements of construction, and it will therefore be observed that the main platform unit 1 is so designed as to provide 10 the opposite occupant supporting or seating surfaces 2 and 3, the former constituting a seat when the device is used as a polycle, as shown in Figure 1 of the drawings, and the latter performing the same function 15 when the platform is reversed to be used as a cart or scooter.

From Figure 1 it will be observed that the said platform 1 consists of a relatively narrow front section 4 and a widened rear 25 seat portion 5 to provide in effect a saddle which the occupant may straddle to conveniently propel the device. The relatively narrow end 4 of the platform has fitted thereto a novel steering unit designated generally as S, while the rear portion 5 carries a novel truck unit T, both of which are capable of adjustably supporting the platform 1 in elevated positions.

Referring first to the steering unit S it 35 is to be observed that the same is held to the platform 1 by means of the opposite bearing blocks 6 and 7 which are bolted or otherwise secured to the platform by the fastenings 8 and project forwardly therefrom to provide the spaced bearing surfaces 40 9 and 10 for the flanged nut or washer elements W of a locking device D, which also includes the bolt 11 that may pierce or pass through the column diametrically, as will 45 later appear. For the purpose of maintaining the proper spaced relation between the forwardly projecting ends of the bearing blocks 6 and 7 a spreader block or filler 12 may be interposed between the front ends 50 thereof and held in place by the fastenings 13. It will therefore be apparent that the said bearing blocks may be accurately maintained in proper spaced relation to provide the necessary clearance to permit of access 55 to the locking device 11 by which the several parts of the vertical steering column are held in place and also adjusted.

The said steering column proper of the unit S may include in its preferred embodiment a pair of opposite post forming members 14 and 15 which are separated by the relatively movable or adjustable intermediate handle carrying section 16, whereby the journal ends *a* and *b* of the members 14 and 15 may be spaced apart as indicated at *c*

below the end of the said member 16 to provide the necessary clearance for the wheel 17. In this embodiment of the invention therefore, the wheel 17 is journalled on the axle unit consisting of the bushing and bolt 70 18 referred to and the said bolt constitutes a support for the oppositely disposed foot rest members 19.

One of the novel and distinctive features 75 of the steering unit is the relatively adjustable and extensible characteristic of the steering column. As previously indicated, the post forming members 14 and 15 may be spaced apart by the intermediate handle carrying member 16, the whole being relatively adjustable in a vertical direction to enable the platform 1 to be elevated to meet the needs of the growing child as well as the section 16 being adapted to be independently 80 elevated. That is to say, the relatively stationary members 14 and 15 are provided with a plurality of adjustment openings 20 for registering with the openings 16^a of the handle section to receive the bolt 11 of the locking device D, whereby when it is desired 85 to elevate the platform 1, the bolt of the locking device may be removed to allow the platform to be freely raised on same to a new position with reference to wheel 17, at the same time permit the handle section 90 16 to be moved upwardly between the parts 14 and 15 a distance corresponding to twice the elevation of the platform, thereby meeting the needs of the growth of the trunk 95 and arms as well as the growth of the legs. 100 Thus it will be seen that the elevation of the platform may be readily effected simultaneously with the adjustment of the handle carrying member 16, whereupon the bolt may be reinserted through the proper 105 openings of both the members 14, 15 and 16 and the cupped washers W brought into bearing relation with the surfaces 9 and 10. It will of course be understood that the rear 110 end of the platform 1 is adjusted vertically to the same height of the front end by adjusting the truck T which will be later referred to.

A further distinctive feature of the invention resides in arranging the hand rest members 23 at one edge of the handle member 16, whereby in the original form of the device the said hand hold members will assume a position relatively close to the seat portion 115 of the platform to accommodate the short 120 arm length of a small child, and, on the other hand by simply reversing the position of the handle member 16 the hand rests 23 may be shifted to the front edge of the steering column to thereby increase the stretch of the 125 arm length by several inches.

For the purpose of maintaining the post forming members 14 and 15 in clamping engagement with the handle member 16 at the upper end of the steering column a suitable 130

holding bolt 24 may be utilized, this holding bolt being also adapted to perform the function of a pivot or fulcrum when the device is used as a cart and the handle member 16 5 performing the function of a tongue by which the cart is pulled.

In view of the foregoing it will be apparent that the steering unit S essentially comprises relatively fixed members which 10 constitute journal supports for the wheel of the steering unit, and which are adjustably connected to the platform, and a relatively telescopic handle member which may be elevated to correspond to the rise or a 15 multiple of the rise in level of the platform and thereby provide a rigid perpendicular handle, said rigidity being due to both bolts 21 and 24 engaging the members 14—16. When the bolt 24 constitutes the only holding 20 means for the handle and acts as a pivot or fulcrum as previously described, the handle serves as a tongue.

The truck unit T is purposely constructed with a view to providing a comfortable seat 25 for the occupant of the device when the same is converted from a car type of toy into a cart, and to this end it will be observed that the said truck unit preferably consists of the opposite legs or pedestals 25 which 30 may be secured to the platform by the fastenings 26. These legs are provided along their rear edge with a plurality of spaced axle receiving openings 27 for enabling the platform to be elevated with reference to the 35 rear axle to correspond with the elevation of the front end on the steering post when used as a car type of toy, and are also provided with another series of spaced openings 28 for performing the same function 40 when the platform is reversed to be used as a cart. The steering unit is of course reversed in the platform when changing from the car type of toy to the cart type by taking apart the wheel and journal supports from 45 the handle section and reassembling in the platform section from the other side.

The opposite legs or pedestal members 25 are preferably maintained in spaced apart relation through the provision of the slat or 50 brace B and are also made further secure by the novel rear axle unit designated generally as 29. This unit comprises a relatively hollow pipe section 30 for abutting against the inner face of the members 25 and 55 is internally threaded to receive the axle bolts 31 for carrying the rear wheels 32 of the truck. It will of course be understood that suitable washers 33 may be employed in connection with the bolts 31 to properly 60 hold the wheels 32 in position. Thus, when the platform is reversed the leg members constitute the sides of the chair-like rest, and also act as guides for the wheels and the transverse web or brace B constitutes the 65 back 34. It will therefore be apparent that

the truck unit T essentially includes a pair of leg or pedestal forming members 25 connected by the brace B, and said legs having adjustable journal bearings for the rear axle unit 29 carrying the wheels 32 arranged on 70 opposite sides of the device.

By reason of the novel formation of the steering unit S and the truck unit T it will be apparent that when the device is used as a straddle vehicle or polycycle, the platform 75 1 may be elevated to any one of five different levels by simply adjusting the front end of the platform on the steering column and also adjusting the rear axle to a corresponding opening of the series 27 in the rear leg or pedestal members 25. In this connection it may also be noted that by securing the opposite ends of the platform in different non-registering positions with reference to the adjustment openings on the steering post 80 and rear truck unit, the said platform may be supported at different inclinations, that is obliquely with reference to the horizontal position assumed by the platform when it is supported in matching or registering positions on the steering post and truck unit. When the device is to be used as a cart that 85 is pulled instead of propelled, the platform 1 may be reversed so that the pedestal members 25 constitute in effect a chair or back 90 rest for the occupant of the vehicle while his feet may be conveniently placed on the foot rests 19. In this form of the toy the handle member 16 is adjusted between the post forming member 14 and 15 to perform 95 the function of a tongue or similar draft member. To enable the tongue to have a relatively free swinging movement on the pivot bolt 24, the nut on the same should not be drawn up tight, but when the device is 100 to be used as a scudder or scooter the handle member 16 may be held rigidly in the upright position by tightening the bolt 24 or by the addition of a like bolt 24a in the adjacent registering holes of member 16 and 110 members 14 and 15 to thereby adjust the entire handle to meet the standing position of the occupant, which is the position assumed in operating a toy of this type.

A modification of the steering post unit 115 is shown in Figure 7 of the drawings wherein a tubular wood or metal post 40 is employed, the same being bifurcated at its lower end 41 to receive the wheel 42 while the upper end telescopically receives an adjustable handle carrying member 44 which constitutes in effect a core. The said handle carrying member 44 is provided with diametrically disposed openings 45 for registering with corresponding openings 46 in 120 the tubular post 40, whereby the adjustment of both the platform and handle carrying member may be effected in the same manner as in Figure 1 of the invention.

A further modification of the steering 125

post is suggested in Figure 8 wherein the column 47 is provided with a transverse slot 48 for adjustably accommodating the handle carrying member 49 while the lower end of said post is formed to provide a journal bearing 50 for the wheel 51.

In Figures 9 and 10 a skeleton type of combined truck and back rest is shown. In this modification the sides or legs 52 of the truck are substantially U-shaped metallic members having adjustment openings 53 in one arm thereof for receiving the axle unit of the truck. For the purpose of bracing the legs 52 against side thrust and also constituting a back rest when the platform is reversed to provide a cart, the said legs 52 are connected by the cross stays 54 shown in Figure 10.

A modified type of foot rest is shown in Figure 11 of the drawings, wherein the axle 55 of the steering unit constitutes means for clamping the oppositely disposed angular pieces 56 in position.

It is also apparent that when reversing the platform from one form of toy to the other it is only necessary to disassemble the handle carrying shaft from the steering post unit, and remove same from the platform and reverse its position with reference to the platform and then reassemble through the post opening in the platform.

Figures 12 and 13 show a still further modified means for rotatably supporting the post of the steering unit by utilizing the locking bolts 11^a and 11^b or their equivalent to bear on the collars or plates *p* and *p'*.

Without further description it is thought that the distinctive structural characteristics of the invention will be readily apparent, and it will therefore be obvious that the device provides a readily convertible toy which fully carries into execution the objects heretofore outlined. That is to say, the invention provides a convertible vehicle including a reversible platform 1 having opposite seating surfaces, one end of said platform being supported by the wheeled steering unit while the opposite end is supported by a combined truck and chair unit which in one form of the vehicle constitutes a truck journal for the rear axle and in the cart form constitutes a chair for supporting the occupant in an upright seated position. And, it will of course be understood, that modifications may be resorted to in connection with minor details of construction without departing from the spirit of the invention or scope of the appended claims.

I claim:

1. A vehicle of the class described including a rear wheeled-truck unit and a steering wheel unit, and a reversible platform having opposite seating surfaces and adapted to be adjustably connected at opposite ends thereof respectively with the steering

wheel unit and the rear truck unit to constitute an occupant propelled vehicle or a type adapted to be pulled.

2. A vehicle of the class described including a wheeled rear truck unit and a front steering wheel, a reversible platform having combined chair-forming and truck constituting journal members fitted to opposite sides thereof and provided with means for adjustably engaging with the axle of the rear wheeled truck unit.

3. A vehicle of the class described including a platform having opposite seating surfaces, a relatively adjustable wheeled steering unit for supporting the front end of said platform whereby the same may be elevated, and a combined rear truck and chair unit for adjustably supporting the rear end of the platform whereby the same may be elevated to different levels and also reversed to convert the toy from occupant-propelled type of vehicle to a type adapted to be pulled.

4. A vehicle of the class described including a platform having opposite seating surfaces, a combined wheel truck and chair unit adjustably supporting the rear end of the platform, and an adjustable wheeled steering unit carrying the front end of said platform and including a relatively fixed post portion and a relatively adjustable handle carrying portion adapted to be vertically adjusted with the platform.

5. A vehicle of the class described including a platform, a wheeled truck unit for supporting the rear end of said platform, and a wheeled steering unit carrying the front end thereof, said steering unit comprising a post consisting of spaced sections and constituting a journal for the wheel of the unit, handle carrying means having a relatively telescopic engagement between said sections, and means for securing the platform and handle in different adjusted positions on the post.

6. A vehicle of the class described including a platform, a wheeled truck unit for supporting the rear end of the platform, a wheeled steering unit for carrying the front end of said platform, said steering unit comprising relatively fixed post means having the wheel of the unit journal therein, an adjustable handle carrying member, and a locking device for securing the platform to the post and also securing the handle carrying means within the post, said locking device including a bolt engaged with bearing elements at each end thereof and providing an extended bearing between the post and the front end of said platform.

7. A vehicle of the class described including a platform, a wheeled truck unit for adjustably supporting the rear end of said platform, and a wheeled steering unit for carrying the front end of said platform, said

- unit including a relatively fixed wheel carrying post provided with adjustment openings, a handle carrying member adjustable with reference to the post and having openings 5 for registering with the openings in the post, and means for securing the front end of the platform and the handle carrying member to the post at any one of a plurality of relatively elevated positions.
10. A vehicle of the class described including a platform, a wheeled truck unit for adjustably supporting the rear end of the platform, and a wheeled steering unit for carrying the front end thereof, said steering unit 15 comprising a wheel carrying member and a relatively adjustable handle carrying member adapted to be locked with the post at any one of a plurality of positions, and also adapted to serve as a hinged tongue when secured to the post by its lower end only.
15. A vehicle of the class described including a reversible platform, a wheeled truck unit for supporting the rear end of said platform, and a wheeled steering unit for 20 carrying the front end thereof, said steering unit including a handle carrying member adapted to be locked with the post at two points to provide a relatively rigid extensible steering column, and also adapted to be 25 secured to the post at one end only to provide a relatively hinged draft tongue.
20. A vehicle of the class described including a reversible platform having opposite seating surfaces, a wheeled combined truck 30 and chair unit for the rear end of said platform, and a wheeled steering unit carrying the front end thereof, said steering unit including a vertically extensible handle carrying member and means whereby the said 35 member may be vertically adjusted coaxially with the axis of the post or pivoted in the line of said axis to constitute a draft tongue.
25. A vehicle of the class described including a reversible platform having opposite seating surfaces, a wheeled steering unit carrying the front end of said platform, and a combined truck and chair unit arranged in the rear end of said platform and including 40 side members, means for connecting said side members to brace the same against lateral thrust and also constitute a back rest, and an axle unit adjustably carried by said 45 side members.
12. A vehicle of the class described including a reversible platform, a wheeled steering unit adjustably supporting the front end of said platform, and a combined truck and chair unit arranged at the rear end thereof said latter unit comprising leg members carried by each side of the platform and having a plurality of aligned openings, a brace connecting said leg members, and wheel carrying axle means adapted to be arranged in said openings. 55
13. A vehicle of the class described including a platform, a wheeled steering unit at the front end of said platform, and a handle carrying member adjustably interlocked with a portion of said steering unit and having hand rest means arranged eccentric to the axis of said member whereby when said member is reversed the said hand rest will occupy a position diametrically opposite the first mentioned position. 60
14. In a vehicle of the class described, a platform, spaced bearing blocks carried by the platform, a front steering unit including a post rotatably mounted in said bearing blocks, and means carried by said post for 65 positioning the platform thereon and constituting a bearing for engaging the upper and lower wear surfaces of said bearing blocks. 70
15. A vehicle of the class described including a reversible platform having opposite seating surfaces, side members secured thereto and projecting to both sides of the opposite seating surfaces of the platform, said side members being provided with a plurality of aligned axle receiving openings, and a wheeled truck unit including an axle adapted to be inserted in the openings at either 75 one face or the other of the platform. 80
16. A vehicle of the class described including a reversible platform, opposite side members having axle receiving openings arranged in relatively oblique alignment to the said platform, whereby the length of the wheel base is increased as the platform is 85 adjusted to higher levels. 90
- In testimony whereof I hereunto affix my signature in the presence of two witnesses.
